UNITED STATES PATENT OFFICE.

WILLIAM G. WALLACE, OF DETROIT, MICHIGAN, ASSIGNOR TO MCCORD RADIATOR & MFG. CO., OF DETROIT, MICHIGAN, A CORPORATION OF MAINE.

RADIATOR.

Application filed September 8, 1924. Serial No. 736,394.

This invention relates to radiators for automobiles and other motor vehicles, and has particular reference to the manner of attaching the tube sheets to the tanks.

5 The main object of my invention is to provide a connection between the tank body and its tube sheet utilizing the resiliency of the sheet metal of the parts for holding the same together on being assembled, thereby 10 avoiding crimping or bending of flanges over each other as heretofore and thus make my invention applicable to radiators with curved or rounded fronts.

The invention consists further in the 15 matters hereinafter described and more particularly set forth in the following claims.

In the accompanying drawings—

Fig. 1 is a front view of a radiator embodying the features of my invention;

20 Fig. 2 is an enlarged horizontal sectional view taken on line 2—2 of Fig. 1;

Figs. 3 and 4 are transverse and longitudinal sectional views, respectively, taken on lines 3—3 and 4—4 of Fig. 2;

25 Figs. 5 and 6 are fragmentary perspective views of the tank and tube sheet, respectively; and

Fig. 7 is a perspective view, partially broken away, of the bottom tank looking at 30 the same from its under side.

Fig. 1 shows a radiator for a motor vehicle having an outer shell or casing 1, and a core 2, as usual in structures of this kind. The core 2 is between upper and lower water tanks 3, 4, and consists of horizontal plates or fin strips 5, 5, through which extend vertical water tubes 6, 6. Each tank has a tube sheet 7 with openings 8 for the tubes or conduits 6 to extend through, as 40 shown.

In the drawings, I have detailed the connection of the tube sheet 7 with the lower tank 4, but it is to be understood that the same showing would apply to the upper tank 3, except that the tank is above the tube sheet instead of below it, as in Figs. 2 to 4.

As illustrated, the lower tank 4 has a body portion having a flat bottom wall 9, and 50 upright rear, end and front walls 10, 11, and 12, respectively. The rear and end walls are substantially flat and straight, while the front wall 12 is curved from one end of the tank to the other with the highest point or 55 crown of the curvature at the center of the

tank, as shown in Figs. 2 and 7. The rear wall 10 has a rearwardly extending horizontal flange 13 along its upper edge. This flange extends from end to end of said wall. The end and front walls 11 and 12 are unflanged, as shown.

Forming the top wall of the tank 4 is the substantially flat tube sheet 7. This member has a shape to fit the top of the tank, and has along its straight rear edge an in-turned flange 14. This flange forms a channel to receive the flange 13 on the rear tank wall 10, as shown in Fig. 3.

About the straight end and curved front edges of the tube sheet 7 is a continuous and unbroken downwardly extending marginal flange 15 designed to slip over the end and front tank walls 11 and 12 on the outside, as shown.

As shown in Fig. 3, the front wall 12 of the tank is curved upward and outward from the bottom wall 9. By so curving the front wall 12, the upper edge of said wall makes the tank normally wider than the tube sheet 7. When these parts are first applied with the flange 13 interlocked with the flange 14, the upper edge of said front wall stands just beyond the flange 15 on the curved front edge of the tube sheet 7. (See dotted lines in Figs. 2 and 3.) Pressing in on the front wall 12, said wall is sprung or flexed inward to slip under the flange 15. At the same time the tube sheet and the tank are pressed together, and by the resilient tendency of the front wall 12 to spring outward the parts are held tightly together on being assembled. To provide for this resiliency, the curvature between the bottom wall 9 and the front wall 12 increases toward the center of the tank from near its ends. This is shown in Fig. 7. This curvature is provided on diepressing the tank out of sheet metal, such as brass. The tube sheet 7 is also pressed to shape out of the same metal.

The connection described utilizes the resiliency of the sheet metal for holding the parts together on being assembled, and thus avoids the necessity of crimping the edges of the tube sheet around flanges on the tank, as heretofore with rectangular tanks. This makes my invention particularly applicable to curved edges, where such crimping could not be employed without checking or wrinkling the metal in the process of making the connection to make leaky joints. Thus

my invention is especially fitted to radiators with rounded fronts, in that it enables water tight joints to be formed about the rounded edges of the tanks of such radiators by soldering after the tanks and tube sheets are applied together.

The details of structure shown and described may be variously changed and modified without departing from the spirit and 10 scope of my invention.

I claim as my invention:

1. A tank for use in a motor vehicle radiator core, having a convex front, said tank comprising a body and a tube sheet covering 15 thereof, both being stamped from sheet metal, said tank body and tube sheet having their front edges curved to conform to the curvature of the convex front of the core, said tank body and tube sheet having interlocking flanges on their rear edges, said tube sheet having a flange on its curved front edge to overlap the curved front wall of the tank body on the outside thereof, the front wall of the tank body being sprung 20 back of said tube sheet flange to engage the same for holding the parts together on being assembled.
2. A tank for use in a motor vehicle radiator core, having a convex front, said tank comprising a body and a tube sheet covering 30 thereof, both being stamped from sheet metal, said tank body and tube sheet having their front edges curved to conform to the curvature of the convex front of the core, said tank body and tube sheet having interlocking flanges on their rear edges, said tube sheet having a marginal flange along its 35 curved front edge and which flange is adapted to overlap the front wall of the tank body 40 on the outside thereof, said tank body at the tube sheet being made slightly wider

than the tube sheet and having its front wall curved back therefrom so that said front wall must be sprung back to engage behind said tube sheet flange for holding the tank 45 body and tube sheet together on being assembled.

3. A tube sheet for a tank of a motor vehicle radiator core having a convex front, said tube sheet comprising a relatively flat 50 body portion stamped from sheet metal and having holes therein for the water conduits of the core, said body portion having its front edge curved to conform to the curvature of the convex front of the core, said body portion having a folded flange on its opposite edge to provide an inwardly facing channel, and a flange on its curved front edge, said flange being at substantially right angles to the body of the sheet and on the 55 same side as the channel.

4. A tube sheet for a tank of a motor vehicle radiator core having a convex front, said tube sheet comprising a relatively flat body portion, stamped from sheet metal and having substantially straight rear and end edges and a curved or rounded frontage, the latter conforming to the curvature of the convex front of the core, said body portion having holes therein, to receive the water 70 conduits of the core and also flanges about its edges, the flange on the rear edge being folded to provide an inwardly facing channel and the flange about the other edges being at substantially right angles to the body of the sheet and on the same side thereof as the channel.

In testimony that I claim the foregoing as my invention, I affix my signature, this 3d day of September, 1924.

WILLIAM G. WALLACE.
